UNITED STATES PATENT OFFICE.

LEWIS W. WOODBURN, OF CHARLESTON, ILLINOIS.

LATCH-KNOB DOOR-LOCK.

No. 857,705.

Specification of Letters Patent.

Patented June 25, 1907.

Application filed July 31, 1905. Serial No. 272,055.

To all whom it may concern:

Be it known that I, LEWIS W. WOODBURN, a citizen of the United States, residing at Charleston, in the county of Coles and State of Illinois, have invented certain new and useful Improvements in Latch-Knob Door-Locks; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in latch knob door-locks, and comprises a simple and efficient means whereby a latch may be actuated by means of a knob, tilted and moved longitudinally by the 20 shaft carrying the knob and in the provision of means for holding the tongue of a key-operated lock, while the latch is being actuated.

The invention comprises various details of construction, combinations and arrangements of parts which will be hereinafter fully described and then specifically defined in the appended claims.

25 The invention is illustrated in the accompanying drawings, which, with the letters of reference marked thereon, form a part of this application, and in which drawings similar letters of reference indicate like parts in the views, in which:—

Figure 1 is a side elevation of my improved lock with one of the side plates of the casing removed showing locking bolt retracted. Fig. 2 is a side elevation with bolt in locked position. Fig. 3 is a perspective view of the lock mechanism. Figs. 4 and 5 are details in 40 perspective.

Reference now being had to the details of the drawings by letter, A designates a door, having a mortised edge for the reception of a casing B, the outer edge of said casing having a slot B' for the reception of the latch C, which has a yoke C' fastened thereto, the rear end of said yoke having angled arms C² against which the arms of the roll-back D are adapted to bear. Suitable guide arms C³ project from the casing of the lock, and are adapted to guide the arms of the yoke as the same may be actuated by the knob shaft. Said roll-back D has an angular outlined aperture therein, which is adapted to receive 55 the knob shaft E, which passes through apertures in the casing of the lock and has knobs

secured thereto. Said latch C has its outer free end cut away, forming an inclined edge c, which is adapted to contact with a stop upon the jamb of the door, said stop having 60 preferably an inclined surface to facilitate the raising of the latch when the door closes.

F designates a bolt which has a recess G formed in the lower edge thereof and also an inverted V-shaped outlined recess O'. The 65 upper edge of said bolt has a lug F' which rises from the edge thereof and H designates a plate mounted upon a pivot I' and is provided with a forwardly projecting portion H' illustrated clearly in Fig. 4 of the drawings 70 and to which is fastened the lower end of a member C⁴ made of a material which will allow of its being elongated longitudinally, the upper end of which member is fastened to a pin J mounted in a recess C³ formed in the 75 latch C.

I designates a bar which is fixed to the side of the plate H and overhangs the bolt F.

H² indicates a lug projecting at right angles from the plate H adjacent to the upper edge 80 thereof and is adapted to form an abutment for the lug F' when positioned upon one side or the other of the latter to prevent the bolt from longitudinal movement.

Rising from the lower portion of the casing 85 is a finger O which extends into the recess G and is adapted to form a stop against the opposite edges of which the ends of the recess G are adapted to contact to limit the longitudinal movements of the bolt F in one direction or the other.

In operation, when it is desired to lock or unlock the bolt, the key is inserted in the keyhole and the tongue of the key coming in contact with the under edge of the plate H, 95 the latter is caused to tilt and the laterally projecting lug H² thereon will be thrown out of the path of the lug F', thus allowing the bolt F to move longitudinally as the tongue of the key comes in contact with one or the 100 other of the edges of the V-shaped slot O'. After the lug F' has passed by the lateral projection H², the spring which is put slightly under tension by the tilting of the plate H and assisted by the weighted end of the plate 105 will cause the latter to tilt back in its normal position with the lug H² positioned upon the opposite side of the lug F', thereby locking the bolt at the limit of its throw in one direction or the other. It will be noted also that, 110 as the latch C is drawn within the casing under the tension of the spring C⁴, the pull

upon the spring will have a tendency to hold the plate H with its lateral projection H² in a locked relation either upon one side or the other of the lug F.

Having thus fully described my invention, what I claim as new and desire to secure by Letters Patent, is:—

In combination with a latch and casing therefor, a knob shaft, and rocking member mounted thereon and adapted for actuating said latch, means within the casing for guiding said latch from longitudinal movement, a longitudinal movable bolt, the under edge of the same being provided with recesses, one of which has inclined edges adapted to be engaged by the bit of a key, a projection upon the casing, a projection extending into the

other recess adapted to limit the throw of the bolt in one direction or the other, a lug projecting from the upper edge of the bolt, a tilting plate mounted within the casing and provided with a lateral extension adapted to contact with one edge or the other of said lug upon the bolt to hold the latter from longitudinal movement in one direction or the other, and an elastic member connecting said plate and latch, as set forth.

In testimony whereof I hereunto affix my signature in the presence of two witnesses.

LEWIS W. WOODBURN.
